US00D920671S

(12) **United States Design Patent** (10) **Patent No.:** **US D920,671 S**
Brunner et al. (45) **Date of Patent:** **** Jun. 1, 2021**

(54) **TOOL BOX**

(71) Applicants: **Keter Plastic Ltd.**, Herzliya (IL);
Milwaukee Electric Tool Corporation,
Brookfield, WI (US)

(72) Inventors: **Yaron Brunner**, Kibbutz Gvat (IL);
Omer Menashri, Kibbutz Afikim (IL);
Izhar Shani, Kibbutz Gvat (IL); **Uri Parizer**, Kibbutz Hukok (IL); **Grant T. Squiers**, Cudahy, WI (US)

(73) Assignees: **Keter Plastic Ltd.**, Herzliya (IL);
Milwaukee Electric Tool Corporation,
Brookfield, WI (US)

(**) Term: **15 Years**

(21) Appl. No.: **29/703,830**

(22) Filed: **Aug. 29, 2019**

Related U.S. Application Data

(62) Division of application No. 29/613,377, filed on Aug. 9, 2017.

(74) *Attorney, Agent, or Firm* — Vorys, Sater, Seymour & Pease LLP; William Klima

(57) **CLAIM**

The ornamental design for a tool box, as shown and described.

DESCRIPTION

FIG. 1 is a top perspective view of one embodiment of a new design of a tool box;

FIG. 2 is a front elevational view of the tool box of FIG. 1; FIG. 3 is a rear elevational view of the tool box of FIG. 1; FIG. 4 is a left side elevational view of the tool box of FIG. 1, the right side elevational view being a mirror image thereof;

FIG. 5 is another top perspective view of the tool box of FIG. 1;

FIG. 6 is a bottom perspective view of the tool box of FIG. 1;

FIG. 7 is a top perspective view of another embodiment of a new design of a tool box;

FIG. 8 is a front elevational view of the tool box of FIG. 7; FIG. 9 is a right side elevational view of the tool box of FIG. 7, the left side elevational view being a mirror image thereof;

FIG. 10 is rear elevational view of the tool box of FIG. 7; FIG. 11 is another top perspective view of the tool box of FIG. 7; and,

FIG. 12 is a bottom perspective view of the tool box of FIG. 7.
